(57) **CLAIM**

The ornamental designs for the prepackaged food display, as shown and described.

DESCRIPTION

FIG. 1 is a front perspective view of a first design for a food display;

FIG. 2 is a back perspective view thereof;

FIG. 3 is a front view thereof;

FIG. 4 is a left side view thereof, the right side view thereof is a mirror image of the left side view.

FIG. 5 is a front perspective view of a second embodiment of the food display;

FIG. 6 is a back perspective view thereof; and,

FIG. 7 is a left side view thereof, the right side view thereof is a mirror image of the left side view.

The front view thereof is identical to that of the first design herein, illustrated in FIG. 3.

The broken lines shown are for illustrative purposes only and form no part of the claimed design.
